UNITED STATES PATENT OFFICE.

FRANK C. STURGES, OF WILKES-BARRÉ, PENNSYLVANIA, ASSIGNOR TO THE
WILKES-BARRÉ MOLDING MACHINE COMPANY, OF PENNSYLVANIA.

MOLD.

SPECIFICATION forming part of Letters Patent No. 443,686, dated December 30, 1890.

Application filed February 7, 1890. Serial No. 339,564. (No model.)

To all whom it may concern:

Be it known that I, FRANK C. STURGES, a citizen of the United States, residing at Wilkes-Barre, in the county of Luzerne, in the 5 State of Pennsylvania, have invented certain new and useful Improvements in Molds, of which the following is a specification.

My improvements relate generally to the construction of sand molds by machinery, and 10 relate particularly to that class of sand molds which are employed in the casting of car wheels, and in connection with, and between the combined sections of which, cast iron or other chills are usually employed.

15 In Letters Patent of the United States No. 360,086, dated March 29, 1887,—No. 360,119, dated March 29, 1887,—No. 371,820, dated October 18, 1887,—No. 408,579, dated August 6, 1889, and No. 409,667, dated August 27, 1889,—are shown described and claimed sundry methods of and apparatus for forming molds for molding car wheels, in the practice of which methods and the operation of which apparatus, a pattern is pressed into the sand, 25 making an imprint, which pattern, by the same operation, rams or compresses the sand to the required density.

It has been found difficult in operating the mechanism and in practicing the inventions 30 embraced in the foregoing patents, to bring the pattern to the precise level of the flask wall, so that the chill, used in the casting of a car wheel, could take its bearing on the rim of the flask, and thus hold the mold firmly in 35 place when it was closed and clamped to receive the metal; thus, if the pattern did not descend to its proper place, the strain on the mold when closed and clamped effected a compression of the sand under and over the chill 40 and thus caused an irregular and defective casting. Again, if the pattern descended below the proper point, the chill, taking its bearing on the edge of the flask, the parts of the mold, the cope, drag, and chill, were prevented 45 from fitting closely together, whereby the molten metal was allowed to escape. To overcome these objections the practice has been to allow the pattern, which is a trifle smaller than the flask to descend into the flask a short 50 distance, and to place the chill on the compressed sand inside the wall of the flask.

This practice in a measure overcame said objections, but was itself objectionable in that the pattern being of only slightly less diameter than the inner wall of the flask, was liable, 55 when in the act of descending into the flask, if for any reason the flask was not accurately centered, to come into contact with the wall of the flask and thus occasion a breakage of the pattern or some portion of the machinery. 60 When the pattern was withdrawn from the flask loose particles of sand, caught between it and the flask, would fall upon the mold and thus necessitate a certain amount of hand labor in order to perfect the mold and put it in 65 proper condition for closing and receiving the metal; and, finally, the chill, taking its entire bearing on the sand, was liable when the mold was subjected to extreme pressure to yield and thus cause an imperfect casting. 70 I overcome all of these objections by adjusting the height of the flask wall, and the point to which the pattern shall descend so that the pattern will under no circumstances descend down to the flask but to a point a short distance above it. I provide a flat surface on 75 the rim of the flask and cause to be distributed upon it, by suitable means, a sufficient quantity of sand, and I extend the pattern so that it will overlap the outer wall of the flask, 80 with the result that in the descent of the pattern the sand on the rim of the flask is compressed to a great degree of hardness. On the compressed sand on the rim of the flask the chill finds a firm and rigid seat which will not 85 yield when the mold is closed and clamped; no hand labor is required to perfect the mold, and there is no danger of breakage by reason of the pattern striking the flask.

In the drawings, Figure 1 is a central sectional elevation of a complete mold provided with a chill, and containing a casting of a double plate car wheel, which mold is of the character shown and described in United States Letters Patent No. 360,086, granted 90 March 29, 1887, to Joseph J. Carr, for method of molding car wheels. Fig. 2 is a central sectional elevation of a flask in which the sand has been distributed in approximately 95 the form into which it is to be subsequently compacted by the pattern. Fig. 3 is a similar view of the same showing a sweep in opera- 100

- tion upon said sand. Fig. 4 is a similar view of the same showing a pattern in place upon the sand, and Fig. 5 is a central sectional elevation of the cope and drag flasks of a mold, 5 which mold embodies my invention and illustrates the relationship which the chill bears to it when its parts are placed together and shows in place in the mold a casting of a double plate car wheel.
- 10 Similar letters of reference indicate corresponding parts.
- Referring first to Fig. 1 it will be seen that the sand contained in each flask is, as to its marginal portion between the matrix proper 15 and the wall of the flask, flush or level with the rim of the flask wall, and that the chill bears against the rim of each of said flasks. The molds in this figure are of the character heretofore in use, and hereinbefore referred to.
- 20 In forming the mold which is the subject of my present application, I charge a walled flask with the sand or other molding material, extend a portion of the sand or molding material to and over the surface of the top of 25 the wall of the flask, and fashion the sand contained in the body of the flask with more or less accuracy into the form into which the sand is to be ultimately compressed; I then occasion the descent of a pattern of sufficient 30 area to extend to the outer circumference of the flask, whereby the sand contained in the flask is compressed and formed into the desired ultimate shape, and the sand on top of the flask wall is compressed into the required 35 density to form the chill seat.
- The following are the details of the operation thus briefly outlined:
- The flask, A, in Fig. 2 is supplied with a quantity of sand, B, and said sand is distributed 40 in any preferred manner within said flask to a form which is, as stated, approximately that of the final desired form. A portion of said sand covers the edge of the wall, a, as shown at b.
- 45 In Fig. 3 is shown a sweep, C, consisting of a rigid arm, c, and a roller, c', of corresponding outline to the arm, both designed to be mounted upon a vertically rotatable shaft,—both of the usual and general construction
- 50 and mode of operation,—and both of sufficient length to extend over and therefore to

operate upon the sand b upon the rim a, as well as upon the sand in the interior of the flask.

In Fig. 4 is shown the flask A and its contained sand B, and also a pattern D, of diameter sufficient to extend to the outer circumference of the flask, and therefore to operate upon the sand b upon the wall a as well as upon the sand contained in the flask,—which pattern is shown as down in place upon the sand. The position which said pattern D is shown in the drawing as occupying, is the lowest which it is designed to reach, and the sand beneath it therefore is in the form which I herein term its ultimate form and in condition to be used in molding a wheel.

In Fig. 5 is shown a mold embodying my invention, it being shown as holding between the cope and drag a chill E, while in the matrix is represented a cast car wheel F.

I do not herein claim or seek to cover the method of forming the mold described, as such method forms the subject of another application for patent executed by me contemporaneously with this application, and filed in the Patent Office upon the 7th day of February, 1890, as Serial No. 339,565.

Having thus described my invention, I claim:

1. In a mold, a walled flask and a quantity of molding material distributed and arranged to form a matrix therein and a bearing upon and extending over the entire upper surface or edge portion of the side inclosing wall thereof, substantially as set forth.

2. In combination, a walled flask and a quantity of molding material distributed and arranged to form a matrix therein and a bearing upon the wall thereof, and a chill adapted to rest upon said bearing surface and supported by said bearing surface out of contact with the metal of the wall, substantially as set forth.

In testimony that I claim the foregoing as my invention I have hereunto signed my name this 29th day of January, A. D. 1890.

FRANK C. STURGES.
In presence of—

EDWARD E. HOYT,
ALEXANDER PATTERSON.
